US00D449887B1

(12) **United States Design Patent** (10) Patent No.: **US D449,887 S**
Haberland et al. (45) Date of Patent: ** Oct. 30, 2001

(54) **COMBINED OBTURATOR, CANNULA AND VALVE ASSEMBLY**

(75) Inventors: **Gary Haberland**, Orlando; **Sam R. Marchand**, Dunedin, both of FL (US)

(73) Assignee: **Genicon LC**, Orlando, FL (US)

(**) Term: **14 Years**

(21) Appl. No.: **29/117,520**

(22) Filed: **Jan. 26, 2000**

(51) LOC (7) Cl. **24-02**

(52) U.S. Cl. **D24/146**

(58) Field of Search **D24/146; 604/164.1, 604/164.2, 165, 185, 192; 606/167, 184, 185**

(57) **CLAIM**

The ornamental design for a combined obturator, cannula and valve assembly, as shown and described.

DESCRIPTION

FIG. 1 is a perspective view of a combined obturator, cannula and valve assembly showing our new design new design; FIG. 2 is a right side elevational view thereof;

FIG. 3 is a left side elevational view thereof; FIG. 4 is a front elevational view thereof; FIG. 5 is a rear elevational view thereof; FIG. 6 is a top plan thereof; FIG. 7 is a top plan thereof; FIG. 8 is a perspective view of the Cannula and Valve Assembly showing our new design new design, with the Obturator removed; FIG. 9 is a right side elevational view thereof; FIG. 10 is a left side elevational view thereof; FIG. 11 is a front elevational view thereof; FIG. 12 is a rear elevational view thereof; FIG. 13 is a top plan thereof; FIG. 14 is a top plan thereof; FIG. 15 is a perspective view of the Cannula showing our new design new design, with the Obturator and Valve removed; FIG. 16 is a right side elevational view thereof; FIG. 17 is a left side elevational view thereof; FIG. 18 is a front elevational view thereof; FIG. 19 is a rear elevational view thereof; FIG. 20 is a top plan thereof; FIG. 21 is a bottom plan thereof; FIG. 22 is a perspective view of the Obturator showing our new design new design; FIG. 23 is a right side elevational view thereof; FIG. 24 is a front elevational view thereof; FIG. 25 is an enlarged fragmentary elevational view of the tip portion, shown in an extended position; FIG. 26 is a left side elevational view of FIG. 23; FIG. 27 is a rear elevational view thereof; FIG. 28 is a top plan thereof; FIG. 29 is a bottom plan thereof; FIG. 30 is a perspective view of the valve showing our new design new design; FIG. 31 is a top plan thereof; FIG. 32 is a bottom plan thereof; FIG. 33 is a front elevational view thereof, the rear elevational view being a mirror image thereto; and, FIG. 34 is a right side elevational view thereof, the left side elevational view being a mirror image thereto.
